UNITED STATES PATENT OFFICE.

LUCIEN LÉON PHILIPPE AND HANS LUGINBUHL, OF PARIS, FRANCE.

OBTAINING BY A SINGLE OPERATION A CORRECT EXPOSURE OF PLATES AND CYLINDERS COMPRISING HALF-TONES ACCOMPANIED BY TEXT OR LINE DRAWINGS FOR HELIO ENGRAVING.

Application filed May 7, 1925. Serial No. 28,728.

To all whom it may concern:

Be it known that we, LUCIEN LÉON PHILIPPE, a citizen of the French Republic, residing at 5 Rue des Lyonnais, Paris, France, and HANS LUGINBUHL, a citizen of the Swiss Confederation, residing at 8 Rue Boucicaut, Paris, France, have invented certain new and useful improvements for obtaining by a single operation a correct exposure of plates and cylinders comprising half tones accompanied by text or line drawings for helio engraving, of which the following is a specification.

This invention relates to a heliographic process principally applicable for plates or cylinders comprising photographs in half tone, surrounded wholly or partially by text or by line drawings.

The object of the process is to enable a simultaneous and correct exposure of the half tones and the text, assembled together on the same plate, to be obtained at a single operation, in other words to enable, during a single exposure, the text or the like to be over exposed to any desired extent and in an automatically controllable manner, as compared with the neighbouring half tones.

By the use of the process, there can be obtained, with very great facility, and without an excessive expenditure of time or labour, that is to say with great economy as compared with the known processes, a plate or cylinder which is immediately ready for etching or treatment in the acid bath and on which there can be produced or etched at a single operation all gradations of tint from intense blacks to absolutely pure whites. The results obtained in practice show that all the intermediate tones are always produced very clearly and correctly in value without hardness, and that the intense whites of the images can be strongly etched without the risk of engraving the ground or background of the text.

In the methods actually employed for obtaining plates or cylinders by helio engraving, half tone elements or transparencies and text elements are assembled, and in order to show the features and economy of the new process, the usual methods will now be summarized under four principal heads or processes, each necessitating numerous and long operations. These processes moreover give very irregular or uncertain results.

In the usual way the positive printing elements—for instance on plates with a gelatine and silver bromide coating—are prepared by regulating the intensity of each transparency by intensifying or reducing, so that a homogeneous whole is produced for exposure. The preparatory stages before etching include framing or masking, removal of the gelatine by scraping around the frame to obtain absolute transparency which is necessary for the production of pure whites constituting the background for the text and preparation of the said text for instance on celluloid film, after which exposure of the carbon paper takes place, the gelatine film of which is to be transferred to the metal preparatory to the etching bath.

First method.—The half tones and the text are produced each on a separate element, then exposed and each engraved separately. In this way two complete operations have to be gone through and it is necessary to cover by means of an insoluble varnish the space for the second transparency until the second operation, and this space must be regulated with great precision.

Second method.—The half tones and the text are again produced each on separate elements and exposed separately and successively, the first exposed portion being covered, for instance by means of a soluble varnish or by black paper, during the second exposure. By varying the time of the respective exposures, over exposure of the text is produced. With this method the etching treatment of the plate or cylinder is effected as a single operation.

Third method.—The half tones and the text are produced on the same plate and the text is over exposed by covering at a suitable time, masking for instance by means of black paper, the part occupied by the half tone photograph. The masks must correspond very exactly to the contour of these photographs. The masking may also be effected by the use of an opaque varnish. With these masks however it is necessary for the operator to leave a rather considerable gap between the text and the illustration to avoid fogged or veiled portions.

Fourth method.—The half tones and the text are produced on the same plate, and the whole exposed during the same exposure

period. Then the portion of the plate or cylinder with the half tone picture is covered with a soluble varnish, which follows exactly the contour of the picture and which is put on very carefully as a coating of uniform thickness. The plate or cylinder thus varnished, when perfectly dry, is plunged into the etching bath, which at once attacks the portion not varnished, comprising the text. The varnish only dissolves at the end of some minutes, then leaving the part comprising the half tones to be attacked. In this way, a difference in the times of treatment in the etching bath is obtained, but this last process requires great attention and experience on the part of a special craftsman, to avoid the white background of the text being attacked in its turn, and especially to obtain correct etching of the picture, which, nevertheless, is nearly always without detail in the intermediate tones.

According to the new process, now about to be described, the exposure and the etching treatment of the plate or cylinder can each be effected at one single operation, and in a very precise manner, giving regular and uniform results.

The positive transparencies or the like, in half tone, prepared in the usual manner, are, preferably before drying, uniformly dyed or tinted over their whole surface, by immersion in a bath of dilute colour, preferably rose or yellow.

After drying and scraping the gelatine, the text which may be printed on celluloid film or in any other manner, is stuck or fixed in place on the same plate. The whole is then given a single exposure to the light, whereupon the text becomes over exposed. The differential duration of exposure can be regulated once for all, by the degree of intensity of the colouring of the half tone portion. The said colouring delays the normal exposure of the half tone portion exactly to any desired degree.

The single operation necessary is therefore slightly to dye or tint the positive printing element to the desired intensity. This very simple and very rapid operation does not require supplementary drying, and involves no special attention as regards the further operations which are themselves simplified.

The new process possesses a further advantage in that the retarding dye forms part of the gelatine surface and is removed therewith by the usual scraping. It does not increase the thickness in the same way as do masks or varnishes. The text can therefore be brought as close as desired to the half tones, even so as to touch them, without causing fogged or veiled portions.

In the accompanying drawings, illustrative of our invention,

Figs. 1, 2, 3, and 4, are plan views of

a photographic plate under different conditions of treatment.

Fig. 5 is a sectional view showing the different elements of a photographic plate assembled for the last operation, i. e., for exposure of the carbon paper etching film.

In Figs. 1 to 4, the parts covered with points or dots, are those which have a stratum of sensitized gelatine; the close oblique hatching lines, indicate, schematically, the image in half tone, with a contour diversified in many ways, while the oblique oppositely directed and spaced hatching lines represent the coloration of the gelatine stratum (Figs. 2, 3, 4).

The horizontal lines shown in Fig. 4, indicate the text printed on celluloid.

As is to be understood, the positive of the image is produced from a negative which has not been retouched, cleaned or otherwise treated, and immediately after its production, and without being dried, is wholly immersed in a bath containing a dilute solution of coloring matter which tints or dyes the whole stratum, as indicated in Fig. 2 by the spaced, oblique hatching lines.

After drying the dyed positive, the stratum or layer of gelatine is scraped away in the usual manner, outside and around the half tone image, so as to leave the glass plate clean and transparent for the application of the celluloid sheet having the printed text. At the same time portions of the gelatine film showing stains, fogs and undesirable features, are removed so as to leave the positive plate in the condition indicated by Fig. 3.

The text, printed on this sheet of suitable transparent material, such as celluloid, cellophane, etc., is arranged upon the glass plate around the image as indicated by the horizontally hatched parts in Fig. 4, the text bearing sheets being of the same thickness as the gelatine film, so as to present an even surface therewith.

This completes the preparation of the dia-positive from which the etching sheet is to be prepared.

It comprises, upon the one plate of glass, the half tone image, on a gelatine film uniformly dyed or stained, and the text printed on transparent sheets, and applied to the clean glass.

The dia-positive being thus complete, requires no further treatment and may be then used for the exposure of the carbon paper etching sheet. But one such exposure is required, as the tinting of the gelatine bearing the half tone image prevents over exposure of the latter.

Fig. 5 illustrates the assemblage of the different elements for this exposure, *b* representing the glass plate, *b'* the gelatine film having the half tone image or illustration, *c*, the celluloid sheet having the text

printed thereon, *a* the carbon paper sheet, with its sensitized gelatine coating *a*¹.

It may be remarked that as a rule the positive printing elements are dyed or tinted before drying, but this is simply to obtain economy in time as compared with drying twice. Obviously the results would be identical if the elements are dyed or tinted after a previous drying; or they may be treated with an alcoholic solution to favour drying.

The restraining or retarding dye or colour may be obtained in any appropriate manner without departing from the principles of the invention. The coating may be of a chemical nature, obtained by dipping, by the use of vapours or it may be of a mechanical nature, obtained by pulverizing, grinding or powdering the material, and it may be applied after or even before development.

What we claim and desire to secure by Letters Patent of the United States of America is:—

1. A photographic diapositive for use in the heliographic process, consisting of a glass plate, part of the surface which is coated with a gelatine film bearing a half tone image and part of which is uncoated with such film, and has attached to it a

sheet of transparent material having text printed thereon, the said gelatine film being tinted, while the text bearing sheet is untinted.

2. The process for the production of heliographic plates or cylinders of the type specified, which comprises the production of a photographic plate of a diapositive of the illustration in half tone, and without previous drying; the immersion of said diapositive in a dyeing solution; the drying of said diapositive; the removal of the gelatine coating from all the parts of the plate surrounding the illustration; the printing of the text upon a transparent support; the attaching the latter to the parts of the diapositive from which the gelatine film has been removed; the production from said diapositive, by a single exposure, of a negative photograph on gelatinized carbon paper; the transfer of the gelatine layer of the carbon paper to a plate or cylinder and the etching of the latter.

In witness whereof we affix our signatures.

LUGINBUHL HANS.
PHILIPPE LUCIEN LÉON.
